FREDERICK WENDLING, OF EDMONTON, ALBERTA, CANADA.

COOLING SYSTEM FOR INTERNAL-COMBUSTION MOTORS.

Application filed April 14, 1921. Serial No. 461,343.

To all whom it may concern:

Be it known that I, FREDERICK WENDLING, a citizen of the United States, and a resident of Edmonton, in the Province of Alberta, 5 Dominion of Canada, have invented new and Improved Cooling Systems for Internal-Combustion Motors, of which the following is a full, clear, and exact description.

10 The present invention relates to new and useful improvements in cooling systems for internal combustion motors, and it pertains more particularly to cooling systems for the motors of motor vehicles and the like. The 15 liquid of these cooling systems is subjected to radiating surfaces in order that the temperature thereof may not rise to too high a degree. In low temperatures this cooling liquid has been compounded with volatile 20 liquids such, for example, as alcohol, glycerine, or the like, in order to lower the freezing point thereof. When the use of these volatile liquids is restored to, under operating conditions of the motor, the volatile 25 liquids are more readily evaporated than the main body of the cooling fluid and pass off in vapor, consequently weakening the cooling fluid.

It is the primary object of this invention 30 to devise means whereby the liquid condensation due to the evaporation of the volatile liquids when used in connection with the cooling fluid of a motor vehicle may be recovered.

35 It is a further object of the invention to provide means whereby this liquid of condensation may be returned to the cooling system of the motor.

It is a further object of the invention to 40 provide automatically operated means for returning the liquid of condensation to the cooling system of the motor.

It is a still further object of the invention to provide a means which in addition to 45 maintaining the liquid level in the cooling system, will supply the motor with moistened air at a point in the intake manifold between the carburetor and the motor, greatly increasing the efficiency of the motor.

50 With the above and other objects in view, reference is had to the accompanying drawings, in which—

Figure 1 is a top plan view of a motor

vehicle chassis showing the general location and arrangement of the parts comprising 55 the present invention;

Fig. 2 is a side elevational view thereof;

Fig. 3 is a detail sectional view taken on the line 3—3 of Fig. 1;

Fig. 4 is a vertical sectional view taken on 60 the line 4—4 of Fig. 1.

Referring more particularly to the drawings, the reference character 5 designates the motor of the vehicle, and said motor is constructed with the usual water-jacketed 65 spaces. The reference character 6 designates the radiator and the water-jacketed spaces of the motor are connected to the radiator by means of a pipe 7 or the like leading from the top of the cylinders to the radiator. 70

The reference character 8 designates the usual overflow pipe of the radiator and instead of having the lower end of said overflow pipe open, as is the common practice, a rearwardly-extending pipe 9 is secured to 75 the lower end thereof as indicated by the reference character 10. The rear end of the rearwardly-extending pipe 9 is connected to a condensing coil or the like 12, said condensing coil terminating in a fitting 13. 80 This fitting 13 is secured in the upper wall of the tank 14 suitably secured to the chassis of the vehicle. Leading from the lower portion of the tank 14, is a pipe 15, and said pipe 15 extends forwardly and into a receptacle 16 carried by the dash, instrument board or other suitable portion of the vehicle adjacent the operator's seat. The tank 14 is formed with a fitting 17, and said fitting has two passages 18 and 19. The passage 90 18 is controlled by means of an inwardly-opening check valve 20, and the passage 19 is controlled by an outwardly opening check valve 21. By means of the inwardly-opening check valve 20, air is permitted to enter 95 the tank 14 for a purpose to be hereinafter described, while the provision of the outwardly-opening check valve 21 permits of an escape of gas pressures should they develop in the tank 14. 100

The receptacle 16 is shown in detail in Fig. 4 and said receptacle has an outlet pipe 22 controlled by an outwardly opening check valve 23. The reference character 24 designates guide rods mounted internally of 105 the receptacle 16, and slidably mounted upon

said guide rods 24 is a float 25. Projecting from the upper face of the float 25 is a needle valve 26, and said valve 26 co-acts with a seat 27 formed in a housing 28. The 5 reference character 29 represents a pipe leading from the housing 28 to the manifold 30 of the motor, whereby the air pressure in the tank 16 is reduced at certain intervals 70 to be hereinafter described. The reference 10 character 35 designates a valve of the needle type, and said valve is manually operated in order that a certain amount of air may be admitted to the receptacle 16 through a pipe 36, this valve serving to relieve the vacuum 15 in the tank 16 under certain conditions. The pipe 15 leading from the rear tank 14 is connected at its forward end to the top wall 75 of the receptacle as indicated by the reference character 37 in Fig. 4.

20 The pipe 22 heretofore mentioned and connected to the lower or bottom wall of the receptacle 16, leads to the water jacket of the motor 5, as indicated by the reference character 33, in order that the liquid contained 25 within the receptacle 16 may be drained directly into the water jacketed 90 spaces of the motor 5.

The device operates in the following manner: Assuming that the water cooling system 30 of the motor 5 including the radiator 6 is filled with a cooling liquid with which is combined volatile liquids, such, for example, as alcohol, glycerine, or the like, and the 35 operation of the motor has been started. The heat generated in the motor causes a vaporization of the volatile oils and in the ordinary course of events, the vapor arising from the liquid level in the radiator 6, would escape through the overflow pipe 8 40 and be lost to the atmosphere. In the present instance, however, this vapor is conveyed by means of the pipe 9 to the condensing coil 12, from whence after condensation, it is conveyed to the rear tank 14. As this evaporation 45 of the volatile fluids takes place, the level in the radiator naturally falls.

From Fig. 2 it will be seen that the tank or receptacle 16 is so positioned with respect to the radiator that the level of liquid in the 50 radiator will coincide with that in the tank 16. Assuming now that the liquid level in the radiator 6 and in the tank 16 falls (it being understood that the level in the tank 16 falls by reason of the pipe 22, which leads 55 to the water-jacketed space of the motor 5,) the float 25 in the tank 16 will also fall. As the float 25 in the tank 16 falls, the valve 26 disengages its seat in the housing 28 and permits of the intake manifold 30 exhausting 60 the air in the top of the tank 16 to form a vacuum therein. Upon formation of the vacuum in the tank 16, the fluid contained in the tank 14 will be discharged by means of the pipe 15, to the tank 16, until 65 the float therein rises to a height sufficient

for the valve 26 to engage the seat in the housing 28, at which time the vacuum-producing means is cut off. By this construction it is apparent that in so long as the vacuum is maintained in the tank 16, immediately upon the fall of the float 25 to the point where the valve 26 moves from the seat 27, a supply of fluid to the tank 16 will be had.

By adjusting the needle valve 35 in such a manner that the same is always slightly open permitting the passage of a very small volume of air into the receptacle 16, the vacuum created in the upper portion of said receptacle 16 will be relieved if for any 80 reason the valve 27 should not properly seat. Owing to the pipe 36 extending below the liquid level in the tank 16, the air admitted to said tank through the valve 35, necessarily passes in the presence of the liquid 85 in the tank 16 and picks up a certain amount of moisture which is carried with the air and introduced to the explosive charge at the point of connection of the pipe 29 with the intake manifold, thus adding to the combustible charge, air laden with moisture, which 90 greatly increases the motor's efficiency.

From the foregoing it will be noted that the present invention provides means whereby the more volatile liquids of the cooling 95 fluid of an internal combustion motor may not only be saved, but may be returned automatically to the cooling fluid.

I claim—

1. A device for collecting the vapors of 100 fluids in internal combustion motor cooling systems comprising a motor, a radiator, an overflow pipe for said radiator, a condenser, a pipe connecting said condenser with said overflow pipe whereby the vapors 105 are conducted through the overflow pipe and said connecting pipe to the condenser, a tank connected with said condenser, a pipe connecting the pipe with the condenser, an auxiliary tank, a pipe connecting the auxiliary 110 with the first-mentioned tank, means connecting the auxiliary tank with the intake manifold of the motor to provide a vacuum in the auxiliary tank, a pipe connecting the auxiliary tank with the water jacket of 115 the motor whereby the contents of the auxiliary tank may be periodically discharged into the water jacket of said motor, and means mounted in the auxiliary tank and adapted to open and close the connection 120 between the auxiliary tank and the intake manifold to automatically shut off the communication between the intake manifold and the auxiliary tank, substantially as described.

2. In a device of the character described, the combination with a motor, a radiator, a condenser connected with the overflow of the radiator, a tank connected with the condenser, an auxiliary tank connected with the 130

first tank and positioned with respect to the radiator so that the level of the liquid in the radiator will coincide with that in the tank, a connection between the top of the auxiliary tank and the manifold of the motor, a float controlled valve in the auxiliary tank and controlling the connection between the

tank and manifold, a connection between the bottom of the auxiliary tank and the water jacket of the motor, and an outwardly opening valve at the junction of said connection with the tank. 10

FREDERICK WENDLING.
